UNITED STATES PATENT OFFICE

ALBERT J. FIESS, OF SYRACUSE, NEW YORK

DESIGN FOR A COMBINED TRAFFIC SIGNAL AND TAIL LIGHT FOR AUTOMOBILES OR THE LIKE

Application filed April 30, 1929. Serial No. 31,047. Term of patent 7 years.

To all whom it may concern:

Be it known that I, ALBERT J. FIESS, a citizen of the United States, residing at Syracuse, in the county of Onondaga and State of New York, and having his post-office address at 107 Sabine Street, Syracuse, New York, have invented a new, original, and ornamental Design for Combined Traffic Signal and Tail Light for Automobiles or the Like, of which the following is a specification, reference being had to the accompanying drawings, forming part thereof.

In the drawings, Figure 1 is a plan view

of this combined traffic signal and tail light, only a fragmentary portion of the support being shown. Figure 2 is a front elevation and Figure 3 is a side elevation thereof.

I claim:

The ornamental design for a combined traffic signal and tail light for automobiles or the like, substantially as shown.

In testimony whereof, I have hereunto signed my name, at Syracuse, in the county of Onondaga, and State of New York, this 5th day of April, 1929.

ALBERT J. FIESS.
